UNITED STATES PATENT OFFICE

124,898

DESIGN FOR A COFFEE URN

Walter B. Law, Dunellen, and George Heaume,
Plainfield, N. J.

Application November 29, 1939, Serial No. 88,566

Term of patent 14 years

To all whom it may concern:

Be it known that Walter B. Law and George Heaume, citizens of the United States, residing at Dunellen and Plainfield, respectively, in the counties of Middlesex and Union, and State of New Jersey, have invented a new, original, and ornamental Design for Coffee Urns, of which the following is a specification, reference being had to the accompanying drawing, forming a part thereof.

We claim:

The ornamental design for a coffee urn, as shown.

WALTER B. LAW.
GEORGE HEAUME.
